UNITED STATES PATENT OFFICE.

CLYDE R. MITTAN, OF VIRGINIA, NEBRASKA.

FRUIT-JAR WRENCH.

Application filed February 23, 1923. Serial No. 620,816.

To all whom it may concern:

Be it known that I, CLYDE R. MITTAN, a citizen of the United States, residing at Virginia, in the county of Gage and State of Nebraska, have invented certain new and useful Improvements in Fruit-Jar Wrenches, of which the following is a specification.

The present invention relates to jar wrenches, the object being to provide a structure that will have an effective gripping action on a jar cap or the like without distorting and injuring the cap, the device automatically positioning itself so as to grip the cap around the top margin thereof where it is reenforced by the top wall of the cap.

The preferred embodiment of the invention is illustrated in the accompanying drawing, wherein:

20 Figure 1 is a plan view of the wrench in its closed position,

Fig. 2 is a similar view illustrating the same open,

25 Fig. 3 is a detail sectional view on the line 3—3 of Fig. 1, and

Fig. 4 is a side elevation showing the wrench in position on the cap of a jar.

In the embodiment disclosed a pair of levers 5 are provided that are pivotally connected between their ends, as illustrated at 6, the arms of the levers at one side of the pivot constituting handles 7, the other arms being preferably flattened and outwardly bowed to form jaw arms, designated 8.

35 The article-embracing jaws preferably semi-circular in form, are shown at 9, and are pivoted together at their rear ends, the pivot being designated 10, and this pivot passing through one of the handle arms 7,

40 as illustrated in Figure 3. A washer 11 may be interposed between the pivoted ends of the jaws 9 and said handle arm. The free ends of the jaws 9 are pivotally connected as shown at 12 to the free ends of the

45 jaw arms 8, and said jaw arms 8 are adapted to abut against each other when the wrench is in its closed position, as illustrated in Figure 1, in which position the handles 7 are preferably in substantially parallel relation. The inner sides of the jaws 9 are serrated, each having oppositely disposed sets of teeth 13 and 14.

Sufficient play is permitted between the pivotal connections and the jaws and levers 55 have sufficient resiliency to allow the ring formed by the jaws 9 to be opened to a con-

siderable extent, as indicated in Figure 2. Therefore when opened the jaws can be placed around the upper rim of a jar cap, as 15 in Fig. 4. When so positioned the pivotal portions of the levers, which extend across the ring constitute a stop or support that will rest upon the top wall of the cap and prevent the jaws passing downwardly too far over the cap. By removing the handles to parallel relation obviously the jaws will be drawn towards each other and engaged with the cap. The opposite set teeth 13 and 14 constitute gripping means that will insure the rotation of the cap with the wrench in either of opposite directions.

Inasmuch therefore as a powerful gripping action can be obtained with a good leverage for turning, it will be evident that caps may be screwed tightly to place or removed from a jar without difficulty and because of the relation and mounting of the article-engaging jaws the levers are made to also perform the function of a positioning device, so that said jaws will engage the upper margins of the cap, which being reenforced by the top wall of such cap, will not be readily deformed.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent, is:

1. A jar wrench, comprising crossed levers pivotally connected between their ends, and article-embracing clamping jaws having their ends pivotally connected to the corresponding ends of the levers and extending rearwardly beyond the pivotal connection between the levers, said levers extending across the space between the jaws.

2. A jar wrench, comprising crossed levers pivotally connected between their ends and having arms on one side of the pivot that are bowed and adapted to abut at their free ends, and article-embracing clamping jaws pivoted to the said free ends of the lever arms and being of greater diameter than the bowed portions of the levers.

3. A jar wrench, comprising crossed levers pivotally connected, and article-embracing jaws pivotally connected together and having such pivotal connection mounted on one of the levers, said jaws and levers being also connected at points spaced from said pivotal connections, and said levers extending across the space between the jaws and at one side of said jaws.
- 10 4. A jar wrench, comprising crossed levers pivotally connected between their ends, forming handles on one side of the pivot, and jaw arms on the opposite side, and article-embracing jaws pivoted together and having said pivotal connection engaged with one of the levers, said jaws being also pivoted to the jaw arms of the levers.
- 15
5. A jar wrench, comprising crossed levers pivotally connected between their ends, forming handles on one side of the pivot 20 and jaw arms on the opposite side, and article-embracing jaws pivoted together and having said pivotal connection engaged with one of the handles of the levers, said jaws being also pivoted at their free ends to the 25 free ends of the jaw arms of the levers and said jaws extending alongside the levers.

In testimony whereof I affix my signature in the presence of two witnesses.

CLYDE R. MITTAN.
